Lawrence Katzman, 614 W. 49th St., New York, N.Y.

Filed Mar. 6, 1961, Ser. No. 64,166

Term of patent 14 years

(Cl. D83—1)

FIGURE 1 is a front perspective view of a combined medicinal steam vaporizer and holder therefor embodying my new design showing the vaporizer separated from the holder;

I claim:

The ornamental design for a combined medicinal steam vaporizer and holder therefor or the like, as shown and described.
